United States Patent Office

Des. 225,923
Patented Jan. 16, 1973

225,923

SEAT

Andrew Ivar Morrison, Brooklyn, and Bruce R. Hannah,
Staten Island, N.Y., assignors to Knoll International,
Inc., New York, N.Y.

Filed May 18, 1970, Ser. No. 33,026

Term of patent 14 years

Int. Cl. D6—02

U.S. Cl. D6—66

Fig. 1.

Fig. 2.

Fig. 3.

Fig. 4.

Fig. 5.

Fig. 6.

Fig. 7.

FIG. 1 is a view in side elevation of a seat showing our design;

FIG. 2 is a view in front elevation;

FIG. 3 is a plan view;

FIG. 4 is a view in rear elevation; and

FIG. 5 is a view in front perspective thereof.

FIG. 6 is a view in front elevation of a modified form of the seat of FIG. 1; and

FIG. 7 is a plan view thereof.

The dominant feature of the design shown in the above figures is a hub structure, which is shown in the figures at the top of each of the vertical legs of the illustrated chairs incorporating such hub structure.

We claim:

The ornamental design for a seat, as shown and described.
